UNITED STATES PATENT OFFICE.

REUBEN HALEY, OF BEAVER, PENNSYLVANIA, ASSIGNOR TO CONSOLIDATED LAMP & GLASS COMPANY, OF CORAOPOLIS, PENNSYLVANIA, A CORPORATION OF PENNSYLVANIA.

DESIGN FOR A SHADE FOR A LIGHTING FIXTURE.

Application filed October 18, 1928. Serial No. 28,530. Term of patent 7 years.

To all whom it may concern:

Be it known that I, REUBEN HALEY, a citizen of the United States of America, residing at Beaver, in the county of Beaver and State of Pennsylvania, have invented a new, original, and ornamental Design for Shades for Lighting Fixtures, of which the following is a specification, reference being had to the accompanying drawings, forming part thereof, in which—

Figure 1 is a side elevation of a shade for a

lighting fixture showing my new design applied to a portion only of the surface of the shade, the design in practice being repeated over the entire surface; and

Figure 2 is a plan view thereof.

I claim:

The ornamental design for a shade for a lighting fixture as shown and described.

In testimony whereof I subscribe my signature.

REUBEN HALEY.
